UNITED STATES PATENT OFFICE.

CHARLES A. BURDICK, OF KENOSHA, WISCONSIN.

PENCIL SHARPENER.

1,421,063.

Specification of Letters Patent. Patented June 27, 1922.

Application filed March 22, 1920. Serial No. 367,836.

To all whom it may concern:

Be it known that I, CHARLES A. BURDICK, a citizen of the United States, and resident of Kenosha, in the county of Kenosha and

5 State of Wisconsin, have invented certain new and useful Improvements in Pencil Sharpeners; and I do hereby declare that the following is a full, clear, and exact description thereof.

10 My invention relates to new and useful improvements in pencil sharpeners and is adapted to particularly provide for adjusting means for the cutting elements thereof.

15 In those pencil sharpeners at present in general use which have revoluble cutting rolls mounted in a rotatable frame, it is impossible to adjust the cutting elements toward or away from each other to either vary the character of the point made on a pencil, 20 or to provide a take-up for adjusting these parts after they have been reground or resharpened. In other words if the diameter of the cutting rolls is changed when the same are reground, they will in all probability 25 cut an imperfect point on a pencil inasmuch as they are spaced more than a normal distance apart.

Consequently it is the primary object of 30 this invention to provide means in connection with a pencil sharpener having rotary cutting rolls whereby the cutting faces thereof may be adjusted toward or away from each other.

It is also an object of this invention to 35 provide means in connection with the other features for adjusting the cutting rolls with respect to the longitudinal center line or axis of the sharpener.

An additional object is to provide a simply 40 constructed pencil sharpener which can be readily adjusted and operated and will be extremely efficient in operation.

With these general objects in view the invention consists in the novel features of 45 construction, combination and arrangement of parts which will be hereinafter more particularly described and claimed.

In the accompanying drawing;

Figure 1 represents a longitudinal sectional view through the operating parts of 50 a pencil sharpener constructed in accordance with the invention, the cutting rolls thereof being diagrammatically represented by means of dot and dash lines.

55 Figure 2 is a transverse sectional view

showing the head which forms one part of the rotary cutting roll supporting frame in elevation.

Figure 3 is a transverse sectional view taken on the plane of the line 3—3 of Figure 60 4 and illustrating an adjusting means somewhat different from that shown in Fig. 1, and

Figure 4 is a detail longitudinal sectional view on the plane of the line 4—4 of Figure 65 3 and showing a second view of the modified adjusting means.

Referring to Figures 1 and 2 of the drawing, it will be seen that the device embodying my improved features of construction is 70 supported as is customary in sharpeners of this character upon a standard or other support 1, which carries a bearing casing 2, one portion thereof being extended as at 3 to form a bearing sleeve for a rotating 75 spindle 4. In the other or main portion of the bearing casing 2 is revolvably mounted a rotary head 5 with which the spindle 4 is connected and which forms one end of a cutting roll supporting frame 6. The 80 outer end of the spindle 4 which projects beyond the bearing sleeve 3 has a crank handle 7 connected thereto whereby the frame 6 may be rotated. This frame is located in a housing 8 which is carried 85 mainly by a radial flange 9 extending from the bearing casing 2.

The frame 6 in addition to the head 5 includes a pencil receiving sleeve 10, a pair of spaced brace bars 11 connecting the head and sleeve, and a pair of diametrically opposed radially extending arms 12 which project from the sleeve 10 adjacent its connection with the brace bars 11. The outer or free end of the sleeve 10 is journaled in one end 90 of the housing 8 and opens therethrough to receive a pencil.

The portion of the head 5 between the brace bars 11 is provided with a central stop rib 13 which is disposed transversely of the 100 axis of the frame 6 and spindle 4, on the center line thereof, but is aligned therewith. Furthermore this stop rib 13 is located in a plane at right angles to the plane of the radially extending arms 12. The brace bars 105 11 adjacent their connection with the head 5 are provided with sight openings 14 which are aligned with the stop rib 13 as clearly shown in Figure 2.

Each of the arms 12 is designed to sup- 110

port one end of a relatively fixed shaft 15, the opposite end of which is reduced to form a pin 16 which is extended through a slot 17 in the head 5 and into a transverse bore 18 therein. The portions of the shaft 15 which engage the arms 12 are screw threaded and loosely disposed in screw threaded holes in the latter. In other words the connection between the arms 12 and shafts 15 is such as 10 to hold the latter against longitudinal shifting except when rotated, while at the same time permitting the axes of said shafts to be moved toward or away from each other.

By such an arrangement the shafts may 15 be adjusted with respect to each other, and the center line of the frame 6 by shifting the pins 16 in the proper direction. This is accomplished by means of adjusting screws 19 which are threaded in the bore 18 of the 20 head 5. One of these adjusting screws is provided for each of the pins 16, and each has an annular groove 20 receiving its pin. Thus either one or both shafts may be shifted at will.

25 It will be noticed from Figure 1 that the axes of the shafts 15 are converged with respect to each other and toward the head 5 so that the pencil engaging faces of the cutting rolls R are positioned at an angle with 30 respect to each other, this angle being similar to that to be formed on a pencil which has been sharpened by the cutting rolls. Inasmuch as the pencil to be sharpened is inserted in the frame 6 longitudinally thereof, 35 it is desirable that the cutting faces of the rolls be disposed equal distances from the center line or axis of the frame 6 and spindle 4. If the rolls are not properly positioned, they can be independently adjusted by 40 means of the adjusting screws 19, the movement thereof toward or away from each other being observable through the sight openings 14. Accurate adjustment is thus readily procured. After the rolls have been 45 properly positioned, they and the frame 6 may be revolved by turning the crank handle 7. Owing to the fact that the rolls are gear connected as at 21 with the relatively stationary bearing casing 2, they will be re-

volved on their shafts 15 as well as with 50 the frame 6.

In Figures 3 and 4 a slightly modified form of the invention is illustrated, the difference between it and the first described type being in the manner of shifting the 55 ends of the shafts which support the cutting rolls, these shafts in Figure 4 being indicated by the reference character 25, having tapered ends 26 for engagement in tapered sockets 27 of a rotary head 28. The 60 outer portions of the sockets 27 are V-shaped as at 29 so that the tapered ends 26 of the shafts 25 may be effectively clamped therein. Movement of the shafts' ends toward or away from each other is obtained by 65 means of adjusting screws 30 which are threaded into bores 31 formed in the head. These adjusting screws have conical heads 32 for engagement with the tapered ends 26 of the shafts 25. The parts associated with 70 the elements shown in Figures 3 and 4 are the same as in the structure depicted in Figure 1, the head 28 being adapted to be journaled in a bearing casing similar to the 75 casing 2 and to be rotated similarly to the head 5.

Various changes may be made in the different parts of the invention as well as in the manner of associating the same together, without departing from the principles as 80 outlined in following claim.

I claim:

A device of the character described comprising a rotary frame, a pair of rotary cutting members carried by the frame and having 85 their shafts converging toward the axis of the frame, a pair of adjusting screws threaded into the frame transversely to the axis thereof and in the same plane with the cutter shafts, circumferential grooves in said 90 screws receiving the ends of the cutter shafts whereby the latter may be adjusted toward or away from the axis of the frame.

In testimony that I claim the foregoing I have hereunto set my hand at Kenosha, 95 in the county of Kenosha and State of Wisconsin.

CHARLES A. BURDICK.
